METHOD OF AND MECHANISM FOR KNITTING RUNPROOF OR RUN-RESISTANT FULL FASHIONED HOSIERY

Ellsworth E. Carlson, Hornell, N. Y., assignor to Van Raalte Company, New York, N. Y., a corporation of New York

Application August 4, 1932, Serial No. 627,447

23 Claims. (Cl. 66—135)

This invention relates to methods of and mechanism for knitting run-proof or run-resistant knitted fabric.

This application is a continuation in part of 5 divisible subject matter contained in my original application Serial No. 541,245, filed June 1, 1931, and is filed in substitution for my co-pending application Serial No. 613,244, filed May 24, 1932, for Mechanism for and method of knitting run- 10 proof or run-resistant full fashioned hosiery and resulting fabric.

In accordance with the preferred embodiment of the invention, the fabric is a plain fabric made upon a full fashioned hosiery machine.

15 In order that the principle of the invention may be readily understood, I have disclosed in the accompanying drawings mechanism for making a full fashioned stocking of the character described in my said original application Serial No. 541,245, 20 and I have also fully illustrated the said stocking.

In said drawings:

Fig. 1 is a plan view of a blank of an English type of full fashioned stocking having my invention 25 applied thereto or incorporated therein, parts being broken away;

Fig. 2 is a side elevation of the complete stocking made in accordance with my invention, but with an intermediate part broken away;

30 Fig. 3 is an enlarged plan view of the fabric viewed from the outside thereof;

Fig. 4 is a similar view, but from the inside or inner face of the fabric;

Fig. 5 is a front elevation of parts only of a 35 full fashioned knitting machine (but representing the parts only diagrammatically), to show how the necessary movements are imparted to the guide bar by which the additional, secondary or warp threads are introduced respectively into 40 each needle wale thereof;

Fig. 6 is a left hand elevation of the structure shown in Fig. 5;

Fig. 7 is a vertical transverse section on the line 7—7 of Fig. 5;

45 Fig. 8 is a front elevation of the right hand end portion of the well-known Reading machine, having my invention applied thereto;

Fig. 9 is an enlarged detail mainly in vertical 50 section of a portion of the means for imparting longitudinal movement to the rod carrying the additional or warp threads to be incorporated into each needle wale of the fabric;

Fig. 10 is an end elevation of the mechanism shown in Fig. 8;

55 Fig. 11 is an enlarged detail mainly in side ele-

vation of means for feeding and tensioning the main knitting thread;

Fig. 12 is a plan view of a part of the means for throwing the additional or warp thread fingers successively out of action to effect fashioning of the fabric; 60

Fig. 13 is a front elevation of the mechanism shown in Fig. 12;

Fig. 14 is a plan view upon a larger scale than Fig. 12 of the additional or warp thread fingers 65 for one section of the machine, and representing also a part of their operating means;

Fig. 15 is a front elevation of the mechanism shown in Fig. 14;

Fig. 16 is an end elevation with parts in vertical 70 section of the mechanism shown in Fig. 15;

Fig. 17 is a rear elevation of a part of the mechanism shown in Figs. 15 and 16;

Fig. 18 is an enlarged view in vertical section and partly in elevation, representing needles, 75 sinkers, knocking over bits, main knitting thread carrier and additional or warp thread guides in their relative positions;

Fig. 19 is a plan view on an enlarged detail of the means shown in Fig. 10 for feeding and tensioning the additional or warp threads; 80

Fig. 20 is a detail in vertical section taken about mid-length of the machine, of a part of the means for taking care of those additional or warp threads that pertain to those needle wales that 85 are discontinued when the fabric or blank is fashioned or narrowed;

Fig. 21 is a detail in elevation of means for operating the shaft shown in Fig. 20 that rotates the spool upon which the additional or warp 90 threads whose needle wales have been discontinued, are wound up, to be disposed of as waste;

Fig. 22 is a side elevation of the mechanism shown in Fig. 21;

Fig. 23 is a plan view of one of the two spools 95 and its supporting means provided for each section of the machine, upon which to accumulate the said additional or warp threads of discontinued needle wales;

Fig. 24 is a side elevation of the means shown 100 in Fig. 23;

Fig. 25 is a somewhat diagrammatic representation of a stocking blank as it comes from the knitting needles, said figure representing the knitting as having progressed into the top of the foot, the stocking blank therefore still being upon the legger;

Fig. 26 is a similar view but representing the 105 stocking blank as now upon the footer;

Fig. 27 is a similar view but representing the knitting as having progressed into the toe;

Figs. 28 and 29 are vertical sections taken through the knitting elements and diagrammatically indicating the position of the fabric when the knitting thereof has progressed to the points respectively indicated in Figs. 26 and 27;

Fig. 30 is a diagrammatic plan view of some of the needles of one section of the machine and indicating the relative positions of the main knitting thread guide or carrier and several of the additional or warp thread fingers in the act of laying their additional or warp threads onto the appropriate needles;

Figs. 31 and 32 are respectively a plan view and a side elevation of the means for automatically varying the traverse of the main thread carrier in accordance with the narrowings or fashionings at the selvage edges and upon the termination of the heel tabs, etc.

Fig. 33 is a plan view of sufficient of one section of the machine to show the means to take care of the warp threads of disconnected needle wales, and

Fig. 34 is a perspective view of the means for automatically varying the traverse of the main thread carrier and for throwing warp thread fingers out of action; and

Fig. 35 is a right hand end elevation of the means for operating said parts.

In my said original application, Serial No. 541,245, filed June 1, 1931, I disclosed a full fashioned stocking, the fabric whereof is constructed in accordance with my invention, and one form or embodiment of means for making said stocking. Herein I have disclosed the same means and in addition I have represented in detail the application of my invention to the well known Reading machine to which or to any other suitable type of full fashioned knitting machine my invention may be applied.

The full fashioned hosiery to which my invention relates is run-proof or very strongly run-resistant in both directions throughout the entire extent of the hosiery.

The machine to which my invention is applied is a full fashioned hosiery machine of any desired type, and in Figs. 8 to 30 I have represented the same as applied to the well known Reading full fashioned machine. My invention is not limited in its application to use on any particular type of full fashioned machine.

The machine is in practice provided with the usual number of sections upon each of which is knitted a stocking leg and the heel tabs and the instep of the foot so as to make an English type of foot, but my invention is not restricted in this respect. In Fig. 5 wherein there is a somewhat diagrammatic representation of parts of a full fashioned knitting machine as well as in Figs. 8 to 30 wherein the invention is represented as applied to a Reading type of machine, I have shown only a single section of the machine, but it is to be understood that each section of the Reading or other type of machine has my invention applied thereto.

Any suitable hosiery yarn or thread may be employed as the main knitting yarn or thread as, for example, silk, artificial silk, rayon, cotton or wool, and I shall use the words "main thread" broadly to include any such types of thread or others that may be suitable. The main thread may be changed from time to time in knitting the stocking as may be necessary, as, for example, at the end of the welt and in the foot. It will be

understood that reinforcing threads may be introduced at desired points, in accordance with practice, particularly in the high splice and in the heel tabs, as well as in the sole and at the toe.

The additional, secondary or warp threads may also be of any suitable material, but they are preferably of silk, and as an important purpose of my invention is to provide a run-stop or strongly run-resistant stocking the stitches whereof so far as the main thread is concerned, are of usual character, I preferably in each instance use additional threads which are of the same character as the main thread, thus giving a uniform structure and appearance to the resulting hosiery, and one which will not be objected to by those who prefer hosiery having the normal or usual stitch so far as the main thread is concerned.

It will be evident that inasmuch as both the main knitting threads and all the warp or additional threads are of the same character (as for example, real silk), the necessary or inevitable slight differences in thickness of the main knitting thread at different parts of its length, due to any cause, will be overcome or neutralized, or very greatly minimized, by reason of the presence of the said warp or additional threads in the respective needle wales of the main thread, inasmuch as the same inevitable inequalities would be present in the said warp and additional threads, and therefore the general effect will be more or less an equalization or distribution of the said inequalities so as to make them substantially non-observable.

Referring first to that form of mechanism shown in Figs. 5, 6 and 7, the framing of the machine is indicated generally at 1, the same having uprights and cross members 2. In the same is suitably mounted the cam shaft 3 driven in any suitable manner and whereon are mounted cams to impart both an axial movement and a rocking movement to a shaft 4 suitably mounted in the upper part of the framing in parallelism with the cam shaft 3. Said axially movable or sliding shaft 4 has suitably secured thereto and depending therefrom all the guide bars 5 for the warp or additional thread fingers, but only one of said guide bars is shown, and that is merely diagrammatically indicated. The shafts 3 and 4 are broken away so that only a small part of the entire machine is shown. The purpose of imparting both an axial or sliding movement and a rocking movement to the shaft 4 is to impart the desired movements to the series of thread guides or fingers 6 for the additional or secondary threads, one such thread guide or finger being provided for each and every needle wale of the stocking blank, so that by reason of the incorporation of the said additional or secondary threads, the stocking is rendered very strongly run-resistant or run-proof in both directions.

It will be understood that I preferably do not transfer stitches inward at the selvages to fashion the fabric at the usual points, in the usual manner, but because of the making of a run-proof fabric as described I am enabled to make the desired fashioning or shaping of the fabric by automatically varying the traverse of the main thread guide or carrier, and I at the same time render inactive or move out of functioning position the guides for the additional threads at the selvages. Such means is not shown in that form or adaptation of my invention represented in Figs. 5, 6 and 7, but is shown in those figures

of the drawings which disclose the application of my invention to a Reading machine. It may be stated at this point, however, that the warp guides or fingers so moved out of functioning 5 position at predetermined times are in total number equal to the number of needle wales at the two selvages at the fabric blank which are, during the knitting of the stocking, terminated by automatically shortening the traverse of the 10 main thread guide or carrier.

Referring further to that form of my invention shown in Figs. 5, 6 and 7, the movements imparted to the guide bar 5 (namely, the longitudinal movement and the rocking movement) give to 15 each thread guide or finger 6 a four way or substantially rectangular movement which is more fully indicated in Fig. 30. The construction is such that each thread guide or finger 6 enters between two next adjacent needles, preferably 20 from the rear to the front, is then moved lengthwise of the machine a distance of one needle, is then swung rearwardly so that each such thread guide or finger 6 passes between the next two needles and is then moved longitudinally in the 25 opposite direction, thereby completing a square or rectangle (see Fig. 30).

While my invention is not in all aspects limited to such a movement of the yarn guides or fingers I preferably restrict each individual warp thread 30 to its own needle wale as this renders the fabric of greater lateral elasticity than a fabric wherein warp threads individually extend into two or more needle wales.

The additional or warp threads are wound upon 35 a suitable warp beam or beams or may be individually supplied from separate bobbins, but I have not attempted to show any such means in Figs. 5, 6 and 7.

It is highly important that the same tension 40 be maintained upon all the additional or warp threads as upon the main knitting thread, and I will in that form of my invention shown in Figs. 8 to 30 disclose means for so doing. In this manner I am enabled to secure a fabric which is of 45 uniform, even and equal tension throughout at both the main knitting thread and the said additional threads.

The needles are desirably spring beard needles and in Fig. 5 are represented at 7 as mounted 50 in a needle bar 8 which is indicated only diagrammatically and which is of any suitable construction. I have not in Figs. 5, 6 and 7 indicated the sinkers, dividers and knocking over bits, nor have I indicated the movements of the knitting 55 needles, but it will be understood that such mechanism functions as in that type of full fashioned hosiery machine to which my invention is applied, whether it be a Reading hosiery knitting machine, as set forth in Figs. 8 to 30, a Schubert & 60 Salzer, a Richter, or a Lieberknecht, or other type.

I have in Figs. 5, 6 and 7 more particularly represented means for imparting the described axial and rocking movements to the shaft 4, but it will be understood that any other suitable means 65 may be employed for the purpose. The said shaft 4 is mounted for axial or sliding movement in the bearings 9, 10 of the framing, and is there secured by a collar 11 between which and the bearing 20 is a suitable coiled spring 12 tending to slide the shaft 4 to the left viewing Fig. 5. At the opposite end of said shaft 4 is secured a roll 13 which takes against a slide 14 having a cam surface 15. The said slide 14 is mounted for vertical sliding movement only, in the bearing 16 provided in a guide bracket 17 secured to one of

the uprights upon the framing. Said slide 14 at its lower end is pivotally secured at 18 to a lever 19 pivoted at 20 upon the framing and having at its opposite end a cam roll 21, and the said cam roll is held constantly in engagement by means 80 of a spring 22 shown in Fig. 5, with a cam 23 fast upon and rotating with the cam shaft 3. The contour of the cam 23 is such as to impart the necessary sliding or axial movements to the shaft 4, so that the additional warp threads will be suitably introduced to the needles 7.

It will be understood that the slide 14 is sufficiently loose in the bearing 16, which is desirably slightly enlarged from its upper to its lower end, to accommodate itself to the very slight arcuate movement imparted by the lever 19.

In order to impart rocking movement to the shaft 4, the latter has fast thereon an arm 24, shown in Figs. 6 and 7 as laterally extending from the said shaft 4, and having suitably connected thereto a rod or link 25 which is mounted for up and down or sliding movement in a bearing 26 upon a guide bracket 27 secured as shown in Fig. 7 to the frame of the machine. The said rod or link 25 has connected thereto a collar 28 to which is connected one end of a coiled spring 29, the other end being secured to the framing of the machine. To the lower end of the rod or link 25 there is pivotally secured at 30 a lever 31, itself pivotally secured at 32 to the framing and having at its other end a roll 33 bearing against the periphery of the cam 34 fast upon the cam shaft 3. The roll 33 is held constantly in engagement with the said cam 34 by the spring 29, and the contour of said cam 34 is such as to impart the necessary rocking movements to the shaft 4, so as to insure the laying of the additional threads in the needles, as already described.

Before proceeding to describe that embodiment of my invention represented in Figs. 8 to 30, I will refer to the fabric which is constructed in accordance with my invention and first make reference to Figs. 1 to 4 inclusive.

In Figs. 1 and 2, the top welt of the full fashioned stocking is represented at 35, and it will be understood that the additional or warp threads, indicated at 36 in Figs. 1, 3 and 4, may be introduced into the fabric from the very commencement thereof (that is, at the very commencement 123 of the welt), or the welt may be made in the usual manner and turned or closed, and thereupon a lighter knitting thread may be substituted, at the same time the additional or warp threads 36 may be introduced and their feeding continued throughout the fabric as will be described in detail.

In Figs. 1 and 2, the leg of the stocking is represented at 37, and referring to Fig. 1, it will be observed that the fabric is narrowed during the knitting of the leg or ankle portion, this being desirably done (as shown in this embodiment of my invention but to which my invention is not limited) by automatically moving out of knitting position two next adjacent thread guides or fingers at each edge of the fabric at every place where a narrowing or fashioning is to be effected. It is to be understood that those warp threads 36 pertaining to the needle wales discontinued at the narrowings, are taken care of in such a way that they do not become entangled in the mechanism during the further operation. In Fig. 1, I have represented the warp threads 36 of the said discontinued needle wales as depending at each side or edge of the fabric. In other figures of the drawing, I have represented one

form of means for automatically taking care of said warp threads of discontinued needle wales.

It will be understood that the traverse of the main thread guide or carrier is automatically varied to correspond to and in accordance with the said narrowings as will be described hereinafter. It will be understood that the warp threads 36 or discontinued needle wales will be subsequently trimmed away.

10 It will also be understood that the stocking blank will be seamed along the selvage edges and also at usual points for an English type of foot as will be further described, but to which type of foot my invention is not restricted.

15 Referring to Figs. 1 and 2, as well as to Figs. 25, 26, 27, and also Figs. 28, 29, which diagrammatically indicate the knitting elements, the instep or top of the foot portion of the stocking is represented at 38, and it will be understood that 20 my invention is of peculiar advantage with the so-called English type of foot because the additional threads 36 continue without interruption from the top of the stocking down the leg and instep to the toe 39. The heel tabs are indicated at 40—40, and at their inner edges are separated from the instep fabric as indicated most 25 clearly at 41—41 in Figs. 1 and 25. The high splice portions are indicated at 42—42, and are provided by the usual additional traversing thread 30 carriers for the reinforcing threads, and the movements of such additional thread carriers are controlled in usual manner. The sole portions of the stocking blank or foot are indicated at 43—43, and the toe portion 39 is provided with 35 the customary narrow 44.

It will be understood that the stocking represented in Figs. 1, 2 and 25 to 29 is seamed along both sides of the foot as indicated at 47 in Fig. 2 and also along the bottom of the foot as indicated at 48 in said figure.

In order that the method of knitting the foot and adjacent parts may be entirely clear, I have, in Fig. 25, indicated the stocking blank as suspended from or coming from the needles 7. In 45 Fig. 25, the knitting upon the legger has progressed to a point at or approximately at the end of the instep, the fabric being upon the needles and above the knocking-over bits in the usual 50 knitting position. The heel tabs 40—40 have been completed and are no longer upon the needles. The fabric is now transferred from the legger to the footer.

The position of the fabric shown in Fig. 26 is that represented in Fig. 28. The instep portion 38 is represented in Fig. 28 and is still upon the needles but below the knocking-over bits 47. To position the instep portion 38 below the knocking-over bits 47, the needle bar 50 is swung away from the knocking-over bits momentarily. The 60 heel tabs 40 are turned outwardly as represented in Fig. 26 and are positioned in customary manner upon the needles and thereupon the sides 43 of the foot are knitted, such fabric being diagrammatically indicated in Fig. 28 as upon the 65 needles 7 above the knocking-over bits. The instep portion 38 is then raised above the knocking-over bits and the knitting continues upon the footer to complete the sides 43 and the toe 39.

It will be understood that the warp threads 36 70 may and preferably do continue throughout the heel tabs 40.

Having thus described one (but diagrammatic) form of means for making the stocking of my invention, and having described such stocking, 75 I will now describe the application of the mech-

anism of my invention to the well-known Reading type of machine, merely for purposes of illustration and without limiting my invention to such type of machine.

In Figs. 8 to 24 and in Fig. 30 I have represented one end portion only of such Reading type of machine, and that merely sufficiently to show the application of my invention to one section thereof, but it is to be understood that all the sections of the machine, whether it be a 80 legger or a footer, are provided with the means for properly introducing the warp threads each into one needle wale of the fabric.

Referring first to Figs. 9 and 10, which are respectively a front and an end elevation of the right hand end of a Reading type of machine, a horizontal portion of the framing is represented at 51. Upstanding therefrom and suitably bolted thereto at each end of the machine frame, there is a bracket 52 and at the inner or left-hand end of the first section of the machine, there is an upright 53 similarly bolted to the frame 51. A bracket such as 53 is provided at each section of the machine. To the upper end of the bracket 52, which is provided at each end 100 of the machine, there is bolted an upright bracket 54. To the upper end of each bracket 53 throughout the machine, there is bolted a duplex bracket as indicated at 55—55 in Fig. 8. It will be understood that one part of the duplex bracket 105 55 and the bracket 54 shown in Fig. 8 are secured together by a tie rod 56 and that a similar tie rod is provided for each section of the machine, and in the intermediate sections of the machine such tie rods secure together members of adjacent duplex brackets 55. A shaft 57 is provided which desirably extends the entire length of the machine, it being indicated at the right of the bracket 54 and between the two parts of the duplex bracket 55. In this embodiment of 110 my invention, but to which my invention is not limited, I provide a single drum or rotary member for all of the warp threads of that stocking blank. Such a drum is indicated in Figs. 8 and 10 at 58. The said drum as well as all such drums 115 are fast upon the shaft 57 as by means of a set screw 59 and suitable tension is imparted or applied to the shaft 57 by a weight 60 secured to the end of a cord 61 passing about a drum or enlargement 62 upon the shaft 57, the 120 cord 61 having its end secured to a pin or screw 63 as shown also in Fig. 10. This construction is repeated at both ends of the machine.

All of the warp threads 36 pass from the drum 58 under a small rod 64 shown in Fig. 10 as resting upon said warps and drawn lightly downward by one or more coil springs 65 connected to a part 66 of the framing. Desirably also the said warp threads 36 pass over and partly about a small roll 67 which lies loosely in a loop or strap 68, the ends of which are connected to a coiled spring 69, itself connected at its opposite end to a screw or member 70 in the framing 66. The rod 67 lies upon the upper edge of the bracket member 66, so as to move to and fro thereon.

By the described means the tension is properly maintained upon all of the warp threads and each of said tensions may be adjusted, and in practice I do from time to time adjust or vary said tension so as to keep the tension upon all 145 of the warp threads the same as the tension upon the main knitting thread. The tension upon the main knitting thread may be and preferably is provided in the usual manner as, for example, as represented in Fig. 11 where is shown a rod 150

71 upon which is rockably mounted a thread carrying or guiding arm 72 having two thread eyes 73, 74, through which pass the main knitting thread 75. A light plate spring 76 is secured to the part 77 of the member 72 and rests upon the rod 78 of the machine, and in operation the member 72 is rocked to tension the threads 75 against the plate spring 76. Any other suitable means may be provided to tension the main thread and I keep, as described, the tension upon all the warp threads uniform with the tension upon the main knitting thread, so that the fabric is of uniform tension throughout. Desirably the main knitting thread and all warp threads are of the same color and otherwise of the same or very similar characteristics, so that the knitted fabric is of uniform character throughout.

The individual warp threads 36 extend through respective openings 79 in a plate 80 shown upon a larger scale in Fig. 19, and the said threads extend thence in a suitably guided manner through the individual thread guides or fingers 81 shown in the several views but upon a large scale in Figs. 16 and 18. The warps may be threaded through said fingers either from the right or from the left as desired.

The guide or carrier for the main knitting thread 75 is represented at 82 in Fig. 18 and elsewhere and is of a usual construction and may be traversed to and fro in a manner usual in a Reading full fashioned knitting machine excepting that I provide means for automatically varying the length of the traverse in accordance with the width of the fabric or blank and accordingly automatically shorten said traverse to correspond with the narrowings, particularly at the calf portion or ankle portion of the leg. I am enabled to do this, and need not fashion the fabric by transferring stitches inward at the two selvage edges as customarily done, because the fabric is of a non-run character throughout, and it is therefore possible to discontinue needle wales wherever desired without tendency of the fabric to run at those points where needle wales are discontinued.

In Fig. 18 a sinker is represented at 83 and a knocking over bit at 47, and the relation of the knitting elements is in said figure indicated, and in Fig. 30 I have diagrammatically indicated the traverse of the main thread carrier 82 along the bank of needles 7. I have also indicated certain of the warp thread fingers 81 in said Fig. 30 and the rectangular movement of the warp thread fingers each about its own needle. It will be understood that the traverse of the main thread carrier 82 across the bank of needles starts substantially simultaneously with the commencement of the thread laying operation of the warp threads 36. It will also be understood that each warp thread is laid once about its needle for each course of the main knitting thread, whether that course starts from the right or from the left end of the bank of needles. The knitting needles commence their descent immediately after each course of the main knitting thread is laid. Each warp thread may be wrapped about its needle in the direction indicated by the arrow heads in Fig. 30 or in the opposite direction. For convenience I prefer to thread the warp threads through the fingers 81 from the right. While the said warp threads are being wrapped about the needles 7, said needles are at their highest position.

I have stated that the traverse of the main

knitting thread carrier is varied or shortened at those times when the fabric is automatically narrowed, and commensurately therewith. I will hereinafter more fully refer to means for varying the traverse of said main knitting thread carrier 82, which carrier is mounted desirably in the customary manner.

Such parts of the Reading machine as are not particularly described may be and preferably are of usual construction and being well known need not be more particularly referred to.

I will next describe the means for mounting the warp thread fingers 81 in such manner that each finger passes rectangularly about its knitting needle and also I will describe means whereby certain of the warp thread fingers are automatically thrown out of action to narrow or fashion the fabric.

In Figs. 8, 9, 15 and 16 and elsewhere there is represented a rod 84 which extends either the entire length of the machine or one half the length thereof, being duplicated for the other half of the machine. Said rod is mounted in suitable brackets one of which is indicated at 85 in Figs. 9 and 10, and at one end said rod is provided with an adjustable bolt 86 against which takes the inclined end 87 of a head or enlargement 88 upon an upright spindle or shaft 89 mounted for axial movement in a bearing or support 90 and moved in a manner to be presently described. Upon the said rod are fast hubs or like members 91, a pair being provided for the warp thread fingers of each section of the machine or bank of needles. To said hubs or members 91 are suitably connected the warp fingers 81 and preferably in the manner indicated more in detail in Figs. 16 and 18. Each hub 91 is desirably of a divided formation and there are provided downwardly extending hub portions 92 supporting a back plate 93 extending the entire length of one section. In alignment at the right and left of the hubs 91, 91, as shown most clearly in Fig. 15, there are provided a series of hubs or collars 93', each of which has depending therefrom or suitably secured thereto two warp fingers 81 which therefore are rigid or fixed with respect to each other. There are thus provided a relatively large number, such as 20 or more warp finger carriers or holders 94 at each side of the fabric blank and sufficient in number to provide for all the narrowings in the calf or ankle portion of the stocking blank and for discontinuing wales at the ends of the heel tabs. It will be understood that in an automatic manner one of said carriers or holders 94 at each selvage edge is thrown out of action at the same time at a narrowing point and that this automatic throwing out of action of one warp thread finger, carrier or holder is continued progressively inward until the narrowings are completed. Those warp thread fingers that remain in action throughout the entire knitting of the stocking blank are all carried by or mounted in a longer block or element which is shown at 95 in Fig. 15 and elsewhere. The block 95 is suitably constructed and supported in such manner that the warp threads introduced thereby are at all times fed to their needles.

In Figs. 15 and 16 are represented at 96 a series of springs mounted on hubs 96', which bear against the front projections of the collars 93' so as to tend to hold the warp thread fingers 81, at the selvage portions, against the back plate 92, but in such manner as to permit the rocking movement indicated in Fig. 18, wherein one of the warp thread fingers 81 is represented as in

a non-functioning position sufficiently toward the front of the machine to prevent the warp thread 36 therefor from being taken by its needle.

While those carriers or holders 94 for the warp thread fingers that are thrown out of action may be acted upon in any suitable manner to render them progressively inactive, I preferably use for this purpose a movement of the machine which is not employed for the purpose of transferring 10 stitches inward, since in the disclosed embodiment of my invention I do not transfer stitches inward, as already explained by me.

While therefore the narrowing points may be and desirably are omitted, I employ the narrowing bars (two in number) for the purpose of causing them successively to throw out of action the warp yarn finger holders 94 one after another progressively inward from the outer edges of the section or bank of needles.

20 For this purpose, I have represented the rod 97 in Fig. 16 upon which is supported the downwardly extending member 98 to support the two bars 99 and 100 which are moved step-by-step in the manner customary with the Reading machine.

It will be understood that the said bars 99, 100 extend the entire length of the machine and that at each section of the machine the bar 100 is provided with a member that moves toward the 30 left so as to engage one after another the holders 94 and that the bar 99 is provided at each section of the machine with a like member but oppositely constructed and oppositely moved, so that in the step-by-step movement thereof toward the right viewing Fig. 15 the holders 94 are one after another moved into non-functioning position.

It will be understood that the said bars 99 and 100 are respectively moved in opposite directions, and in Figs. 12 and 13 I have shown in part the 40 means for giving such opposite movements to the said bar. The members provided respectively upon the bars 99 and 100 are plates 101 shown in Fig. 15, and 102 shown in Fig. 13. Each of said plates is provided with an inclined lower 45 corner portion 103, 104 which, in the opposite inward movements of the bars 99, 100, ride as shown in Fig. 16 upon ears or projections 105 extending substantially horizontally laterally from the holders 94. In the inward movements 50 of said plates 101, 102, the respective pairs of warp threads fingers 81 are thrown into the dotted line position shown in Fig. 18, so that the warp threads are held temporarily in a position where they cannot be taken by the corresponding needles.

I have referred to the rod 84 as axially moved and it is to be understood that said rod is at the same time rocked sufficiently so that the combined movements provide for the wrapping by each 60 warp yarn finger 81 about its corresponding needle 7 in the rectangular manner already referred to. I have in part described means for imparting the axial movement to the rod 84, as consisting of the vertical spindle or shaft 89 of Fig. 9. The shaft 84 is provided with a suitable spring coiled thereabout to return the same after its axial movement, said spring not being shown in Fig. 8 or Fig. 15, because concealed in front thereof. In Figs. 8 and 10 I have more completely shown 65 the means for imparting both the axial and the rocking movement to the rod 84. As therein indicated the shaft 89 at its lower end has pivoted thereto a link 105 at 106. Said link at its lower end is slotted at 107 and is pivotally connected at 70 108 to a lever 109 itself pivotally connected at

110 upon the framing. Said lever 109 carries a roll 111 which rides on a cam 112 fast upon the main cam shaft 113 of the machine. The said cam 112 is provided with a projection 114 which takes under the roll 111 and through the described connections lift the shaft 89 so as to impart an axial movement to the rod 84 of sufficient extent to correspond with the distance between two next adjacent needles. In order to impart the said rocking movement to the rod 84, it is, as shown in Fig. 10, provided with an arm 115, which may be removably connected by a pin 116 to an upright link or bar 117, pivoted to a lever 117' mounted on a bracket 117'', suitably mounted on the framing as indicated in Fig. 10 and carrying at its lower end a roll 118 resting upon a cam 119 also upon the main cam shaft 113. The said cam 119 is provided with a concavity 120 of such extent, shape and position that during the rotation of said cam shaft the rod 84 is rocked sufficiently to move the warp thread fingers 81 from front to back and back to front between adjacent needles.

80 In Fig. 10, I have represented at 121 one of the arms mounted upon a transversely extending shaft 122 and supporting for lengthwise sliding movement the said bars 99, 100. I have also in said figure indicated the path of the main knitting thread 75 to the carrier therefor. It will be observed that the said thread passes through suitable guides, tensions and take-up indicated generally at 123 and which need not be more fully described.

85 I preferably provide means whereby the warp threads of the discontinued needle wales at the narrowings or fashionings are taken care of, so that they will not interfere with or become entangled with the mechanism. For this purpose I have represented one form of means in Figs. 19 to 24, and in Fig. 33, but to which my invention is in no wise limited.

90 In said figures, I have represented the warp threads 36 as coming from the spool or drum provided therefor. At a suitable point adjacent to each selvage portion of each bank of needles 100 I have provided means whereon may be accumulated the warp thread ends of the temporarily discontinued needle wales at the selvages. For this purpose I have in Figs. 20 to 24 and in Fig. 33 represented a portion of the frame at 51. Secured thereto is a bracket 125 supporting for 105 rotative movement a shaft 126 which extends desirably the entire length of the machine and which is at some suitable point or points lengthwise the machine provided with means to rotate 110 the same in a slow step-by-step manner. For this purpose I have represented the main shaft 113 as provided with an eccentric 128 to which is connected a link 129 pivotally connected to and operating an arm or lever 130 loose upon the 115 said shaft 126. Fast upon the shaft 126 is a ratchet 131, the teeth whereof are engaged by a pawl 132, beneath which is a suitable shield 133 moved by a handle 133' and held in position by a pin 133'' to keep the pawl 132 out of the teeth 120 131 at desired times. By the described means or in any other suitable manner, the said shaft 126 is slowly turned step-by-step. At suitable intervals lengthwise the machine, herein at points 125 in general alignment with the selvage portions of each fabric or stocking length, there are provided supporting means such as indicated at 134 for short drums or spools 135, upon which the warp thread ends for the discontinued needle wales are wound, being applied thereto preferably 130 135

by hand by the workman when the knitting of the stocking blank has progressed to such a stage that the warp threads for the discontinued needle wales can be applied to the respective spools 135.

5 Said spools 135 are mounted in open ended bearings and can be readily positioned and removed. Said spools are rotated through the friction existing between the threads accumulating upon the spools 135 and the roll 136 which may, if 80 desired, be suitably roughened at those places where the spools 135 contact therewith. In Fig. 33 are shown the spools 135 at the opposite edges of one stocking blank.

It will be understood from the foregoing description that I have provided warp thread supporting means from which a warp thread extends to each warp finger, and that I have provided means acting to take up the warp thread ends of those needle wales wherat fashioning occurs, 20 and pertaining to which the warp thread ends continue to extend from said warp supporting means. So far as I am aware, no one prior to my invention has made a non-run full-fashioned stocking which is rendered of a non-run character by reason of the provision of a warp thread 25 in each needle wale. Also no one prior to my invention has solved the problem of controlling, without knitting them, those warp ends which pertain to those needle wales which are discontinued in fashioning. I have, as disclosed in 30 the specification and drawings, provided means to control (without knitting them) those warp thread ends that pertain to the needle wales discontinued in or as a part of the act of fashioning. Such control is perfectly effected by taking 35 up said warp ends, as herein disclosed. The said warp ends, being broken by the knitter at a suitable point subsequent to the eye of its warp finger, he applies said warp end directly to the proper take-up roll 135.

I have stated that a certain number of warp finger carriers or holders 94 are progressively thrown into non-feeding or non-functioning position and have stated that such carriers include 45 sufficient warp thread fingers to provide (when thrown out of action) for the fashioning or shaping of the fabric at the selvage edges along the calf or ankle portion. Said carriers or holders 94 also include those warp thread fingers which 50 supply the warp threads for those portions of the fabric where the heel tabs are knitted. When the heel tabs 40 are completed, the holders or carriers 94 whose warp thread fingers supply the warp threads to the heel tabs, are thrown out of action 55 by the continued inward movement of the two bars 99, 100. It is therefore to be understood that the timing of the inward movements of said bars 99, 100 is such that those bars are moved inward toward each other not only at the several 60 points where the shaping or fashioning of the selvages occurs, but also upon the termination of the heel tabs.

In Figs. 31 and 32, I have sufficiently represented automatic means for varying the traverse of the main thread carrier 82. The same is secured as usual to a bar that is moved to and fro and in Fig. 31 I have represented said bar at 136, it being one of seven bars customary in the Reading machine for supporting the several yarn carriers 70 and imparting the requisite movement thereto. The series of said bars is indicated at 137. Adjacent thereto and suitably supported is a screw shaft 138 rotated at the proper times in opposite directions by the ratchets 139. Upon the screw 75 is a nut 140 which is automatically moved inward

or outward at the proper time, by means usual in the Reading machine, and indicated in Fig. 35. Mounted upon the said nut 140 are a series of fingers 141, each in line with one of the bars of the series 137. The appropriate fingers 141 may be thrown in by hand to the position indicated in Fig. 32, and thus provide the stop 142 for the main thread carrier bar 136 in accordance with the fashionings at the selvage edges.

In Figs. 12, 13, 34 and 35 I have sufficiently represented the means for imparting opposite movements to the slide bars 99, 100. As there shown, there is provided a suitably supported shaft 143 oppositely threaded as indicated at 144, 145, and receiving nuts 146, 147 respectively. Extensions 148, 149 from said nuts are secured respectively to said bars 99, 100. The threaded shaft 143 is provided with two oppositely toothed ratchets 150, 151 as well with a holding disk 152. Said ratchets 150, 151 are oppositely automatically rotated in proper timed relation in the usual manner as in the well-known Reading machine so that the slides 99 and 100 are moved toward each other at the times described, thus taking care of all the shapings or fashionings at the selvage and also taking care of the warp thread fingers that supply threads for the heel tabs.

It will be understood that the warp thread fingers which are moved out of functioning position at predetermined times are in total number 105 equal to the number of needle wales at the two selvages of the fabric blank, which are at any time during the knitting of the stocking, terminated by automatically shortening the traverse 110 of the main thread guide.

It will be understood that automatic means are provided for varying, as hereinbefore described, the length of traverse of the main thread carrier 82 at each and every point where the stocking blank should be fashioned and that my invention is not limited to the moving of any particular number of warp thread fingers out of action at any one time. It will be understood 115 that the knitted fabric is taken up in such suitable manner as to secure evenness in the fabric.

Referring to the structure of the fabric which is diagrammatically illustrated in Figs. 3 and 4, it will be understood that the additional or warp threads 36 are interknitted as shown in said figures. The main knitting thread is indicated at 75. Each warp thread 36 is introduced to all the loops of its own needle wale only. Each warp thread 36 lies in parallelism with the loop of the main knitting thread 75 inside the loop and is so uniformly positioned with respect thereto 120 because of the equality of the tension of the main knitting thread and the additional threads, that the fabric and its constituent threads all lie in an even, uniform and equal tension. Therefore, the fabric is as readily expansible as any 125 knitted fabric and is as expansible longitudinally as any knitted fabric is longitudinally expansible. In other words, the incorporation of the additional or warp threads 36, needle wale for needle wale, does not decrease the expansibility 130 of the fabric, nor are the additional threads observable except by a microscopic or similar examination, especially when the main knitting thread 75 and the additional or warp threads 36 are of the same texture, color and character as 135 is desirable and in accordance with my invention. As indicated in Figs. 3 and 4, each warp thread 36 at the top of the loop passes to the back of the previous loop and the corresponding portion of the thread 36 in such loop, and then 140

passes in front of the same down to the next loop when the same has been completed, passing to the back of such loop and then participating in the formation of the next loop in the next course, 5 and the described operation is continued from course to course. The said warp threads 36 do not enter into or become incorporated in the sinker wales, and their presence in the needle wales prevents a run in those needle wales, inasmuch as the additional or warp threads extend lengthwise the wales, whereas the main knitting thread extends transversely of said wales.

Should a break occur in the main thread at any point in a sinker wale, the break cannot extend either up or down the fabric because the main knitting thread will not be released but will be held by adjacent or additional warp threads 36. The loops of said warp threads are knitted symmetrically into and with the loops of 20 the main knitting thread, each warp thread 36 only in its own needle wale, and the fabric is knitted as rapidly as a fabric of plain loops is knitted of only a main thread, so that there is no loss in production and the appearance of the 25 fabric is the same as a plain fabric.

I believe that I am the first to make a full fashioned stocking having incorporated throughout in each needle wale a warp or additional thread knitted only into that single needle wale. 30 and I also believe that I am the first to provide means for knitting such full fashioned hosiery.

It is to be understood that my invention is not limited to the provision of a single warp thread beam or spool for each section of the 35 machine.

I have referred to the fact that the fabric is of a non-run or strongly run-resistant character. If, however, in case the main knitting thread breaks or is cut, in two or more needle wales as 40 well as in the intervening sinker wale or wales, and the break extends to a very few adjacent courses, the warp or additional thread 36 holds and serves to preserve the substantial unity of the fabric both above or below the cut or break 45 and so prevent a run. If a sinker loop breaks, the two ends of the main thread 75 are held or can be held in the needle wales on each side next adjacent to said sinker wales, because of the presence of the warp or additional threads 50 36 in said needle wales and even if the end should pull through in one course, there will be a firm holding in the next or closely adjacent courses.

While my invention is not limited to use in 55 the making of a stocking wherein fashioning or shaping is obtained by varying the traverse of the main thread carrier, I preferably do vary the traverse of the main thread guide or carrier as hereinbefore described.

It will be understood that my invention is not 60 limited to the making of full fashioned hosiery having the English type of foot, nor to any particular type of full fashioned machine, because my invention may be applied to various different types of full fashioned machines as well as to 65 single unit types of machines for knitting hosiery as a flat length. Nor is applicant's invention limited to the introduction of a separate warp thread into each needle wale since within the scope and 70 purpose of applicant's invention the warp threads need only be sufficient in number and approximating closely enough the total number of needle wales so as to render the entire fabric of a non-run or strongly run-resistant character.

75 It will be understood that my invention is ap-

plicable in full fashioned machines without interfering with the usual operation of that machine if it should be desired to use that machine without my invention and to make merely plain fabric. My invention is applicable to all gauges 80 of machines. I have herein stated and I desire to emphasize the fact that the resulting fabric has the same appearance as a plain knit fabric, there being no displaced loops. Moreover, the fabric knitted in accordance with my invention is knitted fully as rapidly as any full fashioned hosiery made of plain loops. Therefore there is no loss whatsoever in production, it not being necessary to slow down the speed of the machine nor to stop the machine during the production 90 of the fabric.

It will, of course, be understood that the warp threads are trimmed off at opposite edges, along the lines of fashioning or narrowing, after the fabric comes from the machine.

Having thus described certain illustrative embodiments of the mechanism of my invention and the best mode known to me for practicing the same, it is to be understood that although specific terms are employed, they are used in a 100 descriptive and generic sense and not for purposes of limitation, the scope of the invention being set forth in the following claims.

I claim:

1. In a full-fashioned hosiery knitting machine 105 having spring beard needles and cooperating sinkers, etc. to form the hosiery throughout of successive courses of regular loops of a main or weft knitting thread; main thread carrier means to traverse said main or weft thread from edge to 110 edge of the hosiery blank; and warp thread guiding fingers, one for substantially every needle, to introduce to substantially every needle and to confine respectively thereto in the knitting operation a separate warp thread, coincidently with the laying of the respective courses of said loops, and including all lateral edge needle wales of the fabric, and to knit the same symmetrically into and with the loops of said wales 115 throughout the lengthwise and transverse extent of said hosiery blank, whereby the hosiery blank is rendered run-proof or strongly run-resistant throughout the entire extent thereof, warp thread supporting means from which a warp thread extends to each warp finger and cooperating means 120 acting upon the main or weft thread at selected courses during the knitting operation to fashion the leg portion of the fabric during the knitting operation while preserving the non-run character of the selvages, and means acting to take up the warp thread ends of those needle wales whereat fashioning occurs and pertaining to which the warp thread ends continue to extend from said 125 warp supporting means.

2. In a full-fashioned hosiery knitting machine having spring beard needles and cooperating sinkers, etc. to form successive courses of regular loops of a main knitting thread; main 140 thread carrier means to traverse said main thread from edge to edge of the hosiery blank; and warp thread guiding fingers, one for substantially every needle, to introduce to substantially every needle a separate warp thread coincidently with the laying of the respective courses of said loops and including all lateral edge needle wales of the fabric, and to knit the same symmetrically into and with the loops of said wales 145 throughout the lengthwise and transverse extent 150

of said hosiery blank; warp thread supporting means from which a warp thread extends to each warp finger, cooperating means acting upon the main or weft thread at selected courses during the knitting operation to fashion the leg portion of the fabric during the knitting operation while preserving the non-run character of the selvages, means acting to take up the warp thread ends of those needle wales whereat fashioning occurs and pertaining to which the warp thread ends continue to extend from said warp supporting means; and tension means for all the threads to maintain the normal transverse and lengthwise expansibility of the hosiery blank whereby a run-proof or strongly run-resistant hosiery blank is produced having the normal expansibility of a plain knitted fabric.

3. In a full-fashioned hosiery knitting machine having spring beard needles and cooperating sinkers, etc., to form successive courses of regular loops of a main knitting thread; main thread carrier means to traverse said main thread from edge to edge of the hosiery blank; and warp thread guiding fingers, one for substantially every needle, to introduce to substantially every needle a separate warp thread coincidently with the laying of the respective courses of said loop and including all lateral edge needle wales of the fabric, and to knit the same symmetrically into and with the loops of said wales throughout the lengthwise and transverse extent of said hosiery blank, including a thread guide bar and means to impart axial movement lengthwise the machine thereto and also back and forth movements, whereby each warp thread is presented only to a single knitting needle, substantially as described; warp thread supporting means from which a warp thread extends to each warp finger and cooperating means acting upon the main or weft thread at selected courses during the knitting operation to fashion the leg portion of the fabric during the knitting operation while preserving the non-run character of the selvages; and means acting to take up the warp thread ends of those needle wales whereat fashioning occurs and pertaining to which the warp thread ends continue to extend from said warp supporting means.

4. In a full-fashioned hosiery knitting machine having spring beard needles and cooperating sinkers, etc., to form successive courses of regular loops of a main knitting thread; main thread carrier means to traverse said main thread from edge to edge of the hosiery blank; and warp thread guiding fingers, one for substantially every needle, to introduce to substantially every needle a separate warp thread coincidently with the laying of the respective courses of said loops and including all lateral edge needle wales of the fabric, and to knit the same symmetrically into and with the loops of said wales throughout the lengthwise and transverse extent of said hosiery blank; warp thread supporting means from which a warp thread extends to each warp finger, cooperating means acting upon the main or weft thread at selected courses during the knitting operation to fashion the leg portion of the fabric during the knitting operation while preserving the non-run character of the selvages; means to render periodically inactive the fingers for those warp threads that are introduced at the selavage portions of the fabric in substantial synchronism with the shaping of the blank; and means acting to take up the warp thread ends of those needle wales

whereat fashioning occurs and pertaining to which the warp guide fingers have been moved into inoperative position.

5. In a full-fashioned hosiery knitting machine having spring beard needles and cooperating sinkers, etc., to form successive courses of regular loops of a main knitting thread; main thread carrier means to traverse said main thread from edge to edge of the hosiery blank; and to vary the extent of said traverse thereby to shape the said blank by discontinuing edge needle wales during the knitting operation; warp thread guiding fingers, one for substantially every needle, to introduce to substantially every needle a separate warp thread coincidently with the laying of the respective courses to said loops and including all subsequently discontinued edge needle wales of the fabric, and to knit the same symmetrically into and with the loops of said wales throughout the lengthwise and transverse extent of said hosiery blank; warp thread supporting means from which a warp thread extends to each warp finger, means to render periodically inactive the fingers for those warp knitting threads that are introduced at the selavage portions of the fabric, in synchronism with the variations of the extent of traverse of the main knitting thread carrier; and means to take up the warp thread ends of those fingers that have been moved into inoperative position.

6. In a full-fashioned hosiery knitting machine having spring beard needles and cooperating sinkers, etc., to form successive courses of regular loops of a main knitting thread; main thread carrier means to traverse said main thread from edge to edge of the hosiery blank; and to vary the extent of said traverse thereby to shape the said blank by discontinuing edge needle wales during the knitting operation; warp thread guiding fingers, one for substantially every needle, to introduce to substantially every needle a separate warp thread coincidently with the laying of the respective courses of said loops and including all subsequently discontinued edge needle wales of the fabric, and to knit the same symmetrically into and with the loops of said wales throughout the lengthwise and transverse extent of said hosiery blank; warp thread supporting means from which a warp thread extends to each warp finger, means to render periodically inactive in small groups at a multiplicity of points along the selvages of the hosiery blank the fingers for those warp knitting threads that are introduced at the selavage portions of the fabric; and means acting to take up the warp thread ends of those needle wales whereat fashioning occurs and pertaining to which the warp thread ends continue to extend from said warp supporting means.

7. In a full-fashioned hosiery knitting machine having spring beard needles and cooperating sinkers, etc., to form successive courses of regular loops of a main knitting thread; main thread carrier means to traverse said main thread from edge to edge of the hosiery blank and to vary the extent of said traverse, thereby to shape the said blank by discontinuing edge needle wales during the knitting operation; warp thread guiding fingers, one for substantially every needle, to introduce to substantially every needle a separate warp thread coincidently with the laying of the respective courses of said loops and including all subsequently discontinued edge needle wales of the fabric, and to knit the same symmetrically into and with the loops of said wales throughout

the lengthwise and transverse extent of said hosiery blank; warp thread supporting means from which a warp thread extends to each warp finger means to render periodically inactive in 5 small groups at a multiplicity of points along the selvages of the hosiery blank the fingers for those warp knitting threads that are introduced at the selavage portions of the fabric in synchronism with the variations of the extent of traverse 10 of the main thread carrier; and means to take up, the warp thread ends of those fingers which are periodically rendered inactive.

8. In a full-fashioned hosiery knitting machine having spring board needles and cooperating 15 sinkers, etc. to form successive courses of regular loops of a main knitting thread; main thread carrier means to traverse said main thread from edge to edge of the hosiery blank; and to vary the extent of said traverse thereby to shape the 20 said blank by discontinuing edge needle wales during the knitting operation; warp thread guiding fingers, one for substantially every needle to introduce to substantially every needle a separate warp thread coincidently with the laying of the 25 respective courses of said loops and including all subsequently discontinued edge needle wales of the fabric, and to knit the same symmetrically into and with the loops of said wales throughout the lengthwise and transverse extent of said 30 hosiery blank; warp thread supporting means from which a warp thread extends to each warp finger means to render periodically inactive in small groups at a multiplicity of points along the selvages of the hosiery blank the fingers for those 35 warp knitting threads that are introduced at the selavage portions of the fabric in synchronism with the variations of the extent of traverse of the main thread carrier; means to take up the warp thread ends of those fingers which are periodically 40 rendered inactive; and tension means for all the threads to maintain the normal transverse and lengthwise expansibility of the hosiery blank.

9. In a full-fashioned hosiery knitting machine having spring beard needles and cooperating sinkers, etc. to form successive courses of regular loops of a main knitting thread; main thread carrier means to traverse said main thread from edge to edge of the hosiery blank and to vary the 45 extent of said traverse thereby to shape the said blank by discontinuing edge needle wales during the knitting operation; warp thread guiding fingers, one for substantially every needle to introduce to substantially every needle a separate warp thread coincidently with the laying of the 50 respective courses of said loops and including all subsequently discontinued edge needle wales of the fabric, and to knit the same symmetrically into and with the loops of said wales throughout the lengthwise and transverse extent of said 55 hosiery blank; warp thread supporting means from which a warp thread extends to each warp finger tension means for all the threads to maintain the normal transverse and lengthwise expansibility of the hosiery blank; means to render 60 periodically inactive the fingers for those warp knitting threads that are introduced at the selavage portions of the fabric, in synchronism with the variations of the extent of traverse of the main knitting thread carrier; and means to keep from the knitting instrumentalities and to take up the warp threads, the guides whereof have been rendered temporarily inactive by which warp threads 65 continue to be delivered.

10. In a full-fashioned hosiery knitting ma-

chine having spring beard needles and cooperating sinkers, etc. to knit full-fashioned hosiery of the so-called English foot type, means to introduce a main knitting thread in successive courses and to continue the introduction of the said thread throughout the leg and the instep portion of the foot; warp thread guiding fingers, one for substantially every needle, to introduce to substantially every needle a separate warp thread coincidently with the laying of the respective courses of said loops and including all lateral edge needle wales of the fabric, and to knit the same symmetrically into and with the loops of said wales throughout the lengthwise and transverse extent of the said hosiery blank including the instep portion of the foot, whereby the hosiery blank is rendered run-proof or strongly run-resistant throughout the entire extent thereof, warp thread supporting means from which a warp thread extends to each warp finger, and means to fashion the fabric by discontinuing needle wales, and means to take up the warp thread ends pertaining to the discontinued wales and which warp ends continue to extend from said warp supporting means.

11. In a full-fashioned hosiery knitting machine having spring beard needles and cooperating sinkers, etc. to knit full-fashioned hosiery of the so-called English foot type; means to introduce a main knitting thread in successive 105 courses and to continue the introduction of the said thread throughout the leg and the instep portion of the foot; warp thread guiding fingers, one for substantially every needle, to introduce to substantially every needle a separate warp 110 thread coincidently with the laying of the respective courses of said loops, and including all lateral edge needle wales of the fabric, and to knit the same symmetrically into and with the loops of said wales throughout the lengthwise and 115 transverse extent of the said hosiery blank including the instep portion of the foot; warp thread supporting means from which a warp thread extends to each warp finger means to render temporarily inactive predetermined fingers for the warp threads, and means to take up the warp thread ends of those needle wales whose warp thread guiding fingers have been rendered temporarily inactive.

12. That method of knitting full-fashioned 125 hosiery which is run-proof or strongly run-resistant throughout the entire extent thereof and including all lateral edge needle wales of the fabric, which comprises the following steps; introducing a main knitting thread and forming there- 130 with course after course of regular loops throughout the extent of the fabric; introducing from a warp thread supply from which a warp thread extends for substantially each needle wale, a separate warp thread into the loops of substantially 135 all the needle wales of the fabric, coincidently with the laying of the respective courses of said loops; knitting the same symmetrically into and with the loops of the said respective needle wales throughout the lengthwise and transverse extent 140 of the hosiery blank; fashioning the leg portion of the fabric during the knitting operation, by acting upon the main or weft thread at selected courses during the knitting operation while preserving the non-run character of the selvages; 145 and taking up the warp thread ends of those needle wales whereat fashioning occurs and pertaining to which the warp thread ends continue to extend from the warp thread supply.

13. That method of knitting full-fashioned 150

- hosier which is run-proof or strongly run-resistant throughout the entire extent thereof and including all lateral edge needle wales of the fabric, which comprises the following steps: introducing a main knitting thread and forming therewith course after course of regular loops throughout the extent of the fabric; introducing from a warp thread supply from which a warp thread extends for substantially each needle wale a separate warp thread into the loops of substantially all needle wales of the fabric coincidently with the laying of the respective courses of said loops, and knitting the same symmetrically into and with the loops of the said respective needle wales throughout the lengthwise and transverse extent of the hosiery blank; varying the extent of traverse of the main knitting thread thereby to shape the fabric and, substantially synchronously with such variations, withdrawing the additional warp threads from functioning position with respect to the needles, but permitting warp thread ends to continue to extend from said warp supply, that pertain to needle wales where said fabric shaping occurs and taking up said warp ends pertaining to said needle wales where shaping occurs.

14. That method of knitting full-fashioned hosiery which is run-proof or strongly run-resistant throughout the entire extent thereof and including all lateral edge needle wales of the fabric, which comprises the following steps: introducing a main knitting thread and forming therewith course after course of regular loops throughout the extent of the fabric; introducing from a warp thread supply from which a warp thread extends for substantially each needle wale a separate warp thread into the loops of substantially all needle wales of the fabric coincidently with the laying of the respective courses of said loops; knitting the same symmetrically into and with the loops of the said respective needle wales throughout the lengthwise and transverse extent of the hosiery blank; fashioning the leg portion of the fabric during the knitting operation, by acting upon the main or weft thread at selected courses during the knitting operation while preserving the non-run character of the selvages; and withdrawing warp threads from functioning relation to the needles at one or more points along each selvage of the blank and upon the completion of the heel tabs, but permitting the said withdrawn warp thread ends to continue to extend from said supply and taking up said withdrawn warp thread ends, while withdrawn from knitting relation.

15. That method of knitting full-fashioned hosiery which is run-proof or strongly run-resistant throughout the entire extent thereof and including all lateral edge needle wales of the fabric, which comprises the following steps: introducing a main knitting thread and forming therewith course after course of regular loops throughout the extent of the fabric; introducing from a warp thread supply from which a warp thread extends for substantially each needle wale a separate warp thread into the loops of substantially all needle wales of the fabric, coincidently with the laying of the respective courses of said loops, and knitting the same symmetrically into and with the loops of the said respective needle wales throughout the lengthwise and transverse extent of the hosiery blank; fashioning the leg portion of the fabric during the knitting operation by acting upon the main or weft thread at selected courses during the knitting opera-

tion while preserving the non-run character of the selvages; and maintaining the normal transverse and lengthwise expansibility of the hosiery blank and at the needle wales where such fashioning occurs permitting the warp thread ends pertaining to fashioning wales to continue to extend from said supply and taking up said warp thread ends pertaining to said fashioning wales.

16. That method of knitting full-fashioned hosiery of the so-called English foot type and which is run-proof or strongly run-resistant throughout the entire extent thereof and including all lateral edge needle wales of the fabric, which comprises the following steps: introducing a main knitting thread and forming therewith course after course of regular loops throughout the extent of the fabric including the leg and the instep portion of the foot; introducing from a warp thread supply from which a warp thread extends for substantially each needle wale, a separate warp thread into the loops of substantially all needle wales of the fabric coincidently with the laying of the respective courses of said loops and knitting the same symmetrically into and with the loops of the said needle wales throughout the lengthwise and transverse extent of the hosiery blank including the instep of the foot; and fashioning the leg portion of the fabric during the knitting operation by acting upon the main or weft thread at selected courses during the knitting operation while preserving the non-run character of the selvages, and at the needle wales where such fashioning occurs permitting the warp thread ends pertaining to fashioning wales to continue to extend from said supply and taking up said warp thread ends pertaining to said fashioning wales.

17. That method of knitting full-fashioned hosiery of the so-called English foot type and which is run-proof or strongly run-resistant throughout the entire extent thereof and including all lateral edge needle wales of the fabric, which comprises the following steps: introducing a main knitting thread and forming therewith course after course of regular loops throughout the extent of the fabric including the leg and the instep portion of the foot; and introducing from a warp thread supply from which a warp thread extends for substantially each needle wale, a separate warp thread into the loops of substantially all needle wales of the fabric coincidently with the laying of the respective courses of the loops; knitting the same symmetrically into and with the loops of the said needle wales throughout the lengthwise and transverse extent of the hosiery blank including the instep of the foot; and fashioning the fabric at the selvage portions by acting upon the main or weft thread at selected courses during the knitting operation and substantially synchronously therewith withdrawing warp threads at the selvage portions where the same is shaped, and permitting the warp thread ends pertaining to fashioning wales to continue to extend from said supply and taking up said warp thread ends pertaining to said fashioning wales.

18. In a full-fashioned hosiery knitting machine having spring beard needles and cooperating sinkers, etc. to form separate courses of regular loops of a main knitting thread; main thread carrier means to traverse said main thread from edge to edge of the hosiery blank; warp thread guiding fingers, one for substantially every needle, to introduce to substantially every needle a separate warp thread coincidently with the laying of the respective courses of said loops;

- warp thread supporting means from which a warp thread extends to each warp finger, means to render periodically inactive the fingers for those warp threads that are introduced at the 5 selvage portions of the fabric and to prevent the knitting of the main or weft thread by those needles whose warp threads are discontinued; and means to take up the ends of those warp threads whose fingers are thrown into non-feeding position.
- 10 19. In a full-fashioned hosiery knitting machine having spring beard needles and cooperating sinkers, etc. to form separate courses of regular loops of a main knitting thread; main thread carrier means to traverse said main thread from edge to edge of the hosiery blank; warp thread guiding fingers, one for substantially every needle, to introduce to substantially every needle a separate warp thread coincidently with 15 the laying of the respective courses of said loops; means to render periodically inactive the fingers for those warp threads that are introduced at the selvage portions of the fabric in substantial synchronism with the fashioning of the blank; 20 means acting upon the main or weft thread at selected courses during the knitting operation to shape the blank, and means at each edge of the blank to take up the warp thread ends of those fingers that are moved into non-feeding 25 position.
- 30 20. In a full fashioned hosiery knitting machine having spring beard needles and cooperating sinkers, etc. to form separate courses of regular loops of a main knitting thread; main thread carrier means to traverse said main thread, from edge to edge of the hosiery blank; warp thread guiding fingers to introduce separate warp threads into substantially all needle wales of the fabric coincidently with the laying of the respective 35 courses of said loops; warp thread supporting means from which a warp thread extends to each warp finger means to render periodically inactive the fingers for those warp threads that are introduced at the selvage portions of the fabric, and to prevent the feeding of the main or 40 weft thread to those needles whose warp threads are discontinued, and means to take up the ends of those warp threads whose fingers are moved into non-feeding position.
- 45 21. In a full-fashioned hosiery knitting machine having spring beard needles and cooperating sinkers, etc. to form successive courses of regular loops of a main knitting thread; main thread carrier means to traverse said main thread from edge to edge of the hosiery blank and to vary the extent of said traverse, thereby to shape the blank by discontinuing edge needle wales during the knitting operation, warp thread guiding fingers, one for substantially every needle, to introduce to substantially every needle a separate warp thread coincidently with the laying of the respective courses of said loops and including substantially all subsequently discontinued edge needle wales of the fabric, those warp thread guiding fingers that supply warps to that width of fabric corresponding to the width of the instep portion being fixedly 50 mounted; and all the other fingers being mounted in small groups to be moved into inactive position, whereby the warp threads are knitted symmetrically into and with the loops of substantially all the wales throughout the lengthwise and transverse extent of the hosiery blank, and whereby, when needle wales are discontinued, the warp thread guiding fingers therefor are moved into inactive position; and means to wind up the warp threads of warp thread guiding fingers that have 55 been moved into inactive position.
- 55 22. In a full fashioned hosiery knitting machine having spring beard needles and cooperating sinkers, etc. to form successive courses of regular loops of a main knitting thread, main thread carrier means to traverse said main thread from edge to edge of the hosiery blank and including means to shorten the extent of said traverse, thereby to shape the blank by discontinuing needle wales during the knitting operation; warp thread guiding fingers to introduce separate warp threads into substantially all needle wales of the fabric coincidently with the laying of the respective courses of said loops, whereby said fabric is rendered of a non-run or strongly run-resistant character 60 throughout including the selvage portion; warp thread supporting means from which a warp thread extends to each warp finger and means actuated automatically in timed relation with the successive shortenings in the extent of the main thread carrier traverse to render periodically inactive the fingers for those warp threads that are introduced at the selvage portions of the fabric, and which discontinued warp thread fingers introduced warp threads only to those needle wales 65 throughout the lengthwise and transverse extent of said hosiery blank, whereby the hosiery blank is rendered run-proof or strongly run-resistant throughout the entire extent thereof, including the said discontinued needle wales; warp thread supporting means from which a warp thread extends to each warp finger narrowing bars and means to move 70 said narrowing bars respectively inward to engage in succession those warp thread guiding fingers that are located to deliver warp threads to needle wales that are to be discontinued, whereby such warp thread fingers are rendered inactive in synchronism with the discontinuance of needle wales, and means to take up the warp thread ends whose guiding fingers have been moved into inactive position.
- 75 23. In a full fashioned hosiery knitting machine having spring beard needles and cooperating sinkers, etc. to form successive courses of regular loops of a main knitting thread, main thread carrier means to traverse said main thread from edge to edge of the hosiery blank and including means to shorten the extent of said traverse, thereby to shape the blank by discontinuing needle wales during the knitting operation; warp thread guiding fingers to introduce separate warp threads into substantially all needle wales of the fabric coincidently with the laying of the respective courses of said loops, whereby said fabric is rendered of a non-run or strongly run-resistant character 80 throughout including the selvage portion; warp thread supporting means from which a warp thread extends to each warp finger and means actuated automatically in timed relation with the successive shortenings in the extent of the main thread carrier traverse to render periodically inactive the fingers for those warp threads that are introduced at the selvage portions of the fabric, and which discontinued warp thread fingers introduced warp threads only to those needle wales 85 throughout the lengthwise and transverse extent of said hosiery blank, whereby the hosiery blank is rendered run-proof or strongly run-resistant throughout the entire extent thereof, including the said discontinued needle wales; warp thread supporting means from which a warp thread extends to each warp finger narrowing bars and means to move 90 said narrowing bars respectively inward to engage in succession those warp thread guiding fingers that are located to deliver warp threads to needle wales that are to be discontinued, whereby such warp thread fingers are rendered inactive in synchronism with the discontinuance of needle wales, and means to take up the warp thread ends whose guiding fingers have been moved into inactive position.
- 95 24. In a full fashioned hosiery knitting machine having spring beard needles and cooperating sinkers, etc. to form successive courses of regular loops of a main knitting thread, main thread carrier means to traverse said main thread from edge to edge of the hosiery blank and including means to shorten the extent of said traverse, thereby to shape the blank by discontinuing needle wales during the knitting operation; warp thread guiding fingers to introduce separate warp threads into substantially all needle wales of the fabric coincidently with the laying of the respective courses of said loops, whereby said fabric is rendered of a non-run or strongly run-resistant character 100 throughout including the selvage portion; warp thread supporting means from which a warp thread extends to each warp finger and means actuated automatically in timed relation with the successive shortenings in the extent of the main thread carrier traverse to render periodically inactive the fingers for those warp threads that are introduced at the selvage portions of the fabric, and which discontinued warp thread fingers introduced warp threads only to those needle wales 105 throughout the lengthwise and transverse extent of said hosiery blank, whereby the hosiery blank is rendered run-proof or strongly run-resistant throughout the entire extent thereof, including the said discontinued needle wales; warp thread supporting means from which a warp thread extends to each warp finger narrowing bars and means to move 110 said narrowing bars respectively inward to engage in succession those warp thread guiding fingers that are located to deliver warp threads to needle wales that are to be discontinued, whereby such warp thread fingers are rendered inactive in synchronism with the discontinuance of needle wales, and means to take up the warp thread ends whose guiding fingers have been moved into inactive position.
- 115 25. In a full fashioned hosiery knitting machine having spring beard needles and cooperating sinkers, etc. to form successive courses of regular loops of a main knitting thread, main thread carrier means to traverse said main thread from edge to edge of the hosiery blank and including means to shorten the extent of said traverse, thereby to shape the blank by discontinuing needle wales during the knitting operation; warp thread guiding fingers to introduce separate warp threads into substantially all needle wales of the fabric coincidently with the laying of the respective courses of said loops, whereby said fabric is rendered of a non-run or strongly run-resistant character 120 throughout including the selvage portion; warp thread supporting means from which a warp thread extends to each warp finger and means actuated automatically in timed relation with the successive shortenings in the extent of the main thread carrier traverse to render periodically inactive the fingers for those warp threads that are introduced at the selvage portions of the fabric, and which discontinued warp thread fingers introduced warp threads only to those needle wales 125 throughout the lengthwise and transverse extent of said hosiery blank, whereby the hosiery blank is rendered run-proof or strongly run-resistant throughout the entire extent thereof, including the said discontinued needle wales; warp thread supporting means from which a warp thread extends to each warp finger narrowing bars and means to move 130 said narrowing bars respectively inward to engage in succession those warp thread guiding fingers that are located to deliver warp threads to needle wales that are to be discontinued, whereby such warp thread fingers are rendered inactive in synchronism with the discontinuance of needle wales, and means to take up the warp thread ends whose guiding fingers have been moved into inactive position.
- 135 26. In a full fashioned hosiery knitting machine having spring beard needles and cooperating sinkers, etc. to form successive courses of regular loops of a main knitting thread, main thread carrier means to traverse said main thread from edge to edge of the hosiery blank and including means to shorten the extent of said traverse, thereby to shape the blank by discontinuing needle wales during the knitting operation; warp thread guiding fingers to introduce separate warp threads into substantially all needle wales of the fabric coincidently with the laying of the respective courses of said loops, whereby said fabric is rendered of a non-run or strongly run-resistant character 140 throughout including the selvage portion; warp thread supporting means from which a warp thread extends to each warp finger and means actuated automatically in timed relation with the successive shortenings in the extent of the main thread carrier traverse to render periodically inactive the fingers for those warp threads that are introduced at the selvage portions of the fabric, and which discontinued warp thread fingers introduced warp threads only to those needle wales 145 throughout the lengthwise and transverse extent of said hosiery blank, whereby the hosiery blank is rendered run-proof or strongly run-resistant throughout the entire extent thereof, including the said discontinued needle wales; warp thread supporting means from which a warp thread extends to each warp finger narrowing bars and means to move

ELLSWORTH E. CARLSON.
